CLAIM

The ornamental design for a flying spinning toy, as shown and described.

DESCRIPTION

FIG. 1 is a top perspective view of a flying spinning toy; FIG. 2 is a bottom perspective view of the flying spinning toy of FIG. 1;

FIG. 3 is a top view of the flying spinning toy of FIG. 1; FIG. 4 is a bottom view of the flying spinning toy of FIG. 1;

FIG. 5 is a front view of the flying spinning toy of FIG. 1; FIG. 6 is a back view of the flying spinning toy of FIG. 1; FIG. 7 is a right side view of the flying spinning toy of FIG. 1; and,

FIG. 8 is a left side view of the flying spinning toy of FIG. 1.

The broken lines shown in the views are included for the purpose of illustrating portions of the flying spinning toy that form no part of the claimed design.
